FISHING LURE

Eugene L. Sandburg, Minneapolis, Minn.

Application December 6, 1955, Serial No. 39,180

Term of patent 14 years

(Cl. D31—4)

FIG. 1

FIG. 2

FIG. 3

FIG. 4

FIG. 5

Figure 1 is a perspective view of the fishing lure, showing my new design.

Figure 2 is a plan view of the fishing lure from the top.

Figure 3 is a side elevation of the fishing lure.

Figure 4 is a plan view of the fishing lure showing the bottom thereof.

Figure 5 is a end view of the fishing lure from the front thereof.

I claim:

The ornamental design for a fishing lure, as shown.
